UNITED STATES PATENT OFFICE.

DAVID FRIEDMAN, OF ROXBURY, MASSACHUSETTS.

BRACKET NAIL.

Application filed September 8, 1922. Serial No. 586,872.

To all whom it may concern:

Be it known that I, DAVID FRIEDMAN, a citizen of the United States, residing at Roxbury, in the county of Suffolk and 5 State of Massachusetts, have invented new and useful Improvements in Bracket Nails, of which the following is a specification.

The object of my said invention is the provision of a simple, easily manufactured 10 and inexpensive bracket nail—i. e., a device susceptible of being quickly fixed in position by hammer blows and without turning of the device, and one adapted to serve as a bracket for securely supporting articles of 15 different kinds without rendering the articles unsightly and also adapted to serve for the suspension of an article other than the one supported by the bracket nail.

To the attainment of the foregoing, the 20 invention consists in the improvement as hereinafter described and definitely claimed.

In the accompanying drawings, forming part of this specification:—

Figure 1 is a side elevation of one embodiment of my invention.

Figure 2 is an enlarged perspective of the same.

Figure 3 is a side elevation of a slight modification.

Figure 4 is an enlarged perspective showing the manner in which said modification can be used as a curtain-rod hook.

Similar numerals designate corresponding parts in Figures 1 and 2 to which reference will first be made.

My novel bracket nail is appropriately formed of one piece of metal compatible with its purpose, and among other features has a tapered shank 1 with a sharp point 2.

40 It also has an arm 3 extending at right angles from the heel portion of the shank together with a driving head 4 aligned with the shank and a notch 5 between the upper portion of the driving head 4 and the base 45 of the arm 3. Between the inner side of the arm 3 and the upper side of the shank 1 the nail is preferably, though not necessarily, provided with a sharp corner 6 adapted to snugly receive and fit the sharp 50 corner of an article of rectangular cross-section.

It will be apparent from the foregoing that a few taps of a hammer is all that is necessary to fix my sharp pointed bracket nail in support, no turning being necessary 55 and the time consumed by such operation being saved which is particularly important when the bracket nails are used by high-salaried window dressers. It will also be apparent that the hammer blows are applied to the head 4 so that the nail can be 60 truly driven without liability of distortion of any part thereof. After the nail is driven and an article placed thereon to be supported by the nail, a picture cord can be 65 safely hung from the head 4; the notch 5 forming a secure seat for the bight of said cord.

In the embodiment shown in Figures 1 and 2 the outer side of the upper end of the 70 arm 3 is preferably, though not necessarily, beveled as designated by 7 so as to merge into the surface of the article supported and increase the finished appearance of the device when in use.

75 The embodiment shown in Figures 3 and 4 is designed more particularly to support a curtain rod 8 after the manner clearly shown in Figure 4. In all essential respects it is similar in characteristics to the form shown in Figures 1 and 2 though it differs from said form in that its arm 3^a is of circular cross-section and terminates in a rounded end 7^a, and in that its junction portion 6^a is arcuate in order to snugly 80 conform to the circular cross-section of a curtain rod or the like.

I have entered into a detailed description of the construction and relative arrangement of the parts embraced in the present and preferred embodiments of my invention in order to impart a full, clear and exact understanding of the said embodiments. I do not desire, however, to be understood as confining myself to the specific construction and relative arrangement of parts inasmuch as in the future practice of the invention various changes and modifications may be made such as fall within the scope of my invention as defined in my appended claim.

Having described my invention, what I

claim and desire to secure by Letters Patent, is:—

A nail of the class described comprising a straight shank having one end enlarged to provide a circular driving head, said shank tapering to a point from the head to the other end thereof, and a straight arm integral with the shank and projecting lat-

erally from the latter adjacent the head, said arm being adapted to project upwardly 10 from the shank in use, the inner end of the arm being spaced from the head, substantially as and for the purpose described.

In testimony whereof, I affix my signature:

DAVID FRIEDMAN.
